US0D1057727S

(12) **United States Design Patent** (10) **Patent No.:** **US D1,057,727 S**
(45) **Date of Patent:** **** Jan. 14, 2025**

(54) **STAND WITH DISPLAYS**

(71) Applicant: **Elo Touch Solutions, Inc.**, Knoxville, TN (US)

(72) Inventors: **Brian Perry**, Knoxville, TN (US); **Jeffrey Haller**, Redwood City, CA (US); **Kenneth North**, San Carlos, CA (US); **Fareed Uddin**, San Jose, CA (US)

(73) Assignee: **Elo Touch Solutions, Inc.**, Knoxville, TN (US)

(**) Term: **15 Years**

(21) Appl. No.: **29/945,764**

(22) Filed: **Jun. 5, 2024**

Related U.S. Application Data

(63) Continuation of application No. 29/881,846, filed on Jan. 6, 2023, now Pat. No. Des. 1,036,451.

(57) **CLAIM**

The ornamental design for a stand with displays as shown and described.

DESCRIPTION

FIG. 1 is a front isometric view of a stand with displays showing the claimed design;

FIG. 2 is a rear isometric view thereof;

FIG. 3 is a front elevation view thereof;

FIG. 4 rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the figures show portions of the stand with displays that form no part of the claimed design.

1 Claim, 7 Drawing Sheets
